UNITED STATES PATENT OFFICE.

JOSEPH KUEN, OF MELROSE PARK, PENNSYLVANIA.

MULTIPLE-SURFACE EVAPORATOR.

1,245,469.

Specification of Letters Patent.

Patented Nov. 6, 1917.

Application filed December 14, 1914. Serial No. 877,260.

To all whom it may concern:

Be it known that I, JOSEPH KUEN, a citizen of the United States, residing at Melrose Park, in the county of Montgomery and 5 State of Pennsylvania, have invented certain new and useful Multiple-Surface Evaporators, of which the following is a specification.

The purpose of my invention is to provide novel pans for condenser or evaporator use as well as convenient and dependable means for connecting the parts whereby assemblage and removal of the individual pans, grids and connected parts are facilitated and the operations shortened.

A further purpose of my invention is to make the bottoms and sides of the several pans used separable from the grids and from the steam supply and discharge connections 20 for heating them.

A further purpose of my invention is to split the inlet steam manifold up into sections; each corresponding to a part of the heating system only, preferably to a single 25 grid and pan, making each of the pans and heating connections separable as a unit from adjoining units.

A further purpose of my invention is to utilize the steam inlet and discharge connections 30 as ends for the pans.

A further purpose of my invention is to protect the outlet from each pan against discharge of foam.

A further purpose of some forms of my 35 invention is to support the pans wholly or partially from the heating grids.

A further purpose of my invention is to control the inlet of fluid to the first of a series of pans in the same container by the 40 depth of fluid in one of the pans and to determine the rate of flow by regulating the rate of withdrawal of fluid from the container.

Further purposes of my invention will 45 appear in the specification and claims hereof.

I have preferred to illustrate my invention by several forms thereof which have proved to be practical, efficient and relatively 50 inexpensive and which at the same time well illustrate the principles thereof.

Figure 1 is a central vertical longitudinal section of one form of my invention, through the shell or casing showing the parts, chiefly

in elevation, but partly broken away and 55 partly in section upon line 1-1 of Fig. 2.

Fig. 2 is an end elevation of the structure seen in Fig. 1, with one of the heads removed and with parts in section on line 2-2 of Fig. 1.

Fig. 3 is a partly broken perspective view of one of the pans shown in Figs. 1 and 2.

Fig. 4 is a partly broken top plan view of the pan of Fig. 3, with heating grid and connections assembled therein.

Fig. 5 is a partly broken central vertically longitudinal section of a second form of my invention.

Fig. 6 is a section of the structure shown in Fig. 5, taken upon the lines 6-6.

Fig. 7 is a partly broken perspective view of the type of pan shown in Figs. 5 and 6.

Fig. 8 is a partly broken top plan view of the pan of Fig. 7, with the heating grid and connections inserted therein.

Fig. 9 is a detail sectional view of a part of the structure seen in Fig. 7.

Fig. 10 is an elevation, partly broken away and sectioned, of a modification of the first form of my invention.

Similar numerals of reference indicate like parts in the drawings.

While my invention will for convenience be treated herein as applied to evaporators and particularly to multiple effect evaporators, it will be obvious that the same features which make the structures shown highly advantageous as an evaporator will also enhance their utility as a condenser; and that the individual evaporator or condenser units shown are desirable whether used separately or as parts in producing multiple effects.

In each of my forms I have shown a single cell comprising a casing and a plurality of 95 pans or trays presenting separate evaporating or condensing surfaces and superimposed so that, for evaporation, the residuum from one tray may supply the material for evaporation in the next. Each of these cells 100 is capable of separate use or may form but one among a number of cells in a multiple effect system.

The cell jackets or casings 1, 1' (Figs. 1 and 5) may be of any desired shape to accommodate the form of pan or tray desired and are shown as provided with end casings 2, 2', 3, 3' opposite the ends of the pans for

convenient access in assemblage of the parts and removal for cleaning and repairs. Both are shown as removable in Fig. 1; whereas the end 2' is permanently attached in Fig. 5, 5 with a removable hand hole cover 2² therein.

The casings are provided with blow-off pipes 4, valved at 5. In Fig. 1 the lower part of the casing is connected with a float chamber 6, by means of piping 7 and 8 entering the casing respectively below and above the intended liquid level 9 of the residuum from the lowermost evaporating pan. It will be noted that in this case, as well as in the form of Fig. 10, this residuum is 10 stored temporarily in the bottom of the casing, whereas, in the form shown in Fig. 5, the residuum is temporarily stored in the lowermost tray or pan and correspondingly connected with a float chamber by pipes 7' 15 and 8 to maintain the level 9' in said chamber. 20

The fluid intended to be evaporated is introduced to the uppermost of the pans 10, 10' through any suitable pipes, 11, 11', 25 valved at 12 and delivering the fluid at any points 13, 13'. The float 14 moves a rod 15 to increase or decrease the opening of a valve 16 in the pipe 11 or 11', by which the entrance of fluid into the upper pan is 30 controlled by the height of the liquid level 9 or 9', making the entrance of fluid proportionate to the rate of withdrawal of the residuum from the storage, whether from the bottom of the tank, (Figs. 1 and 10), 35 or bottom pan (Fig. 5).

The steam supply is admitted at 17 to the manifold 18 and passes through a series of sets 19, 19' of grid passages, here conveniently made up of pipes 20, discharging 40 into the header 21 or 21'. The header is vented at 22, 22', through a valve 23, and is connected by pipe 24 to any suitable trap. Separable connections at 25, 25' (Figs. 1 45 and 5) provide for ready disconnection of the steam inlet. The trap and vent pipes may also be disconnectible as at 26, 26' in Figs. 1 and 5.

Taking up the first form:—The trays 10 are open-ended, as seen best in Fig. 3 and 50 are connected to the steam manifold sections and header at their ends by laterally extended heads 27 and 28. The connection is made by any suitable means, here shown as bolts 29, operating through ears 30 on the 55 head and engaging ears 31 upon opposite ends of the trays. The outer contours of the respective heads at these points correspond with the inner contours of the trays so that the trays are effectively joined to 60 the heads by the bolt and ear construction indicated. The heads form closures for the ends of the trays, thus completing the pans. The heads are provided with walls 32 of sufficient height to correspond with the required height of sides 33 of the trays, co-

operating with them to prevent discharge of the liquid from the edges of the pans through foaming. It will be noted that in this form the trays do not form complete pans, as they are without ends. The ends 70 of the pans are supplied by the inlet and discharge connections of the grid system.

The manifold at the steam receiving end of the pans, is made up of a series of sections 34, preferably formed integral with the laterally extended parts 27 and capable of assemblage in the manner best seen in Fig. 1, so as to make a continuous steam manifold when in position. Each manifold section is thus permanently connected to a 80 grid, comprising a distributing steam connection, the grid pipes and a discharge connection from the pipes. This construction permits removal of that section of the manifold which forms the end of any particular 85 pan after removal of the attaching bolts 35 from the ears 36 of the adjoining parts. The removal of a section is much facilitated by separating the adjoining manifold sections from the one to be removed, and moving one adjoining section longitudinally of the manifold, to allow room for withdrawal of the section in a direction parallel to the length of the tray (and also of the pan) and grid pipes. 90

Among many means of longitudinal separation and re-assemblage of the parts, which will occur to the engineer, I disclose but one, resting the lower end of the sectional manifold upon an adjustable support by 100 which the sections which are not bolted fast to the inlet pipe, may be allowed to drop with respect to those which are so supported from the inlet. The adjustable support shown comprises upper and lower support members 37, 38, joined by right and left threaded coupling 39. The support member 37 carries a plate 37' which closes the lower section of the manifold. The nut 39 affords positive means for forcing the 110 sections upwardly into firm and effective contact when ready for re-assemblage. 105

At the discharge ends of the grids, each head 28 terminates in a single flange 40 about a single opening with which all of the pipes 115 are connected. These flanges are secured to flanges 41 upon the discharge header 21. Any desired packing is used to insure a tight joint in all of the steam connections indicated. 120

The laterally extended parts 27 of the manifolds are rigidly joined to the head 28 by the tubes 20 which lie in the bottoms of the pans and are intended to be covered by the liquid being evaporated. All of the 125 tubes are thus connected between the inlet and discharge so as to be effective for heating purposes.

I show expansion joints 42 and 43 in the steam connections at the discharge end, in 130

order to avoid strains due to differences of temperature. Since these expansion joints are common to the end connections of all of the pans in my structure, no separate expansion need be provided for in the pans.

I prefer to have the liquid enter each pan near one end thereof, and discharge each of the pans into that next below it, through an outlet 44, whose upper edge 45 is raised

- 10 to a height above the bottom of the pan to act as a weir and maintain the desired level of liquid in the pan. To avoid passage of foam from one pan to the next, I protect the discharge by a guard, shield, or deflector 46, which in this form surrounds the weir and prevents direct approach at levels above the weir. The shield is apertured at 47 in its lower part, preferably having the upper edge of the aperture below the
- 15 upper edge 45 of the weir and extends above the aperture and about the weir to a height, as at 48 here shown as approximately corresponding to the height of the sides 33 and ends of the pan.

20 The residuum from the evaporating process will, of course, be less than the fluid received at 13, 13' by the amount of the evaporation and this reduction is progressive throughout the pans.

25 In the form of Fig. 1, I prefer to have the flow in adjoining pans in reverse directions and therefore place their outlet openings at opposite ends.

30 In operation, the steam supply (from the next higher stage or pressure, if used in a multi-stage evaporator) enters through the pipe 17 into the manifold at the left of Fig. 1, where it is distributed through the grids of the several pans and discharged to the

35 trap and vent. The liquid to be evaporated is received in the top pan and flows over its weir and through its outlet into the next pan, proceeding successively in this way until discharged from the final pan into the bot-

40 tom of the container. Meantime, if operating as a multi-stage evaporator, the evaporation from the several pans causes vapor pressure lower than that of the steam supply but high enough to be effective as sup-

45 ply for the next lower evaporator and this vapor is discharged to the next lower stage through pipe 49.

50 The liquid in the bottom of the casing may be withdrawn through blow-off pipe 4, or 55 from the float chamber or connections or in any other way as desired, preferably at a regular rate. One means of controlling this rate is shown in Fig. 10. Its level regulates the rate of inlet liquid entering the top pan

60 by the float chamber and connections to valve 16.

At intervals, the grids and trays may be removed for cleaning. Since the grids need cleaning more frequently than the trays I

65 have made no provision in this form for lat-

eral displacement of the trays to facilitate removal of the trays separately. With the construction in Fig. 1, it is necessary to withdraw the manifold section, and grid with each tray. The tray may then be separated from the grid for greater accessibility in

70

In the form shown in Fig. 5, the casing is of different shape and the manifold, heads, trays, header and connections of these parts differ from those of Fig. 1. The trays here have ends and constitute pans. The pipe 7 connects with the lowermost pan, instead of the bottom of the casing and the vent and trap pipes for the header pass through the end 2' in a direction substantially parallel with the length of the grids so as to allow for expansion. Stuffing boxes 50, 51, 52 prevent leakage where these pipes pass through the casing.

75

The manifold 18' and header 21' are both continuous throughout their lengths and are provided with single openings and flanges at 53 about the openings for receipt of the tubular ends 54, 55 of heads 56 and 57 through which the steam is distributed to and received from the pipes of the grids. The tubular ends are flanged at 58 and 59 and the flanges of the grid heads are secured to the manifold and header by bolts 60.

80

The head 56 is high enough close to the manifold to clear the end 61 of the pan and is bent downwardly a short distance inside the pan, as at 62 so that the grid will lie close to the bottom of the pan without requiring bending of the individual pipes. The point 62 is so chosen as to provide for some movement of the grid pipes and head 56 from and toward the end 61 of the pan to permit insertion and withdrawal of the tubular end 55 of the head 57. This end is extended about a portion of its circumference as shown at 63, to carry the steam and gases from each grid beyond the drainage of condensation from that or those grids located above it; and also to form a projection which, as the tubular end moves to the right in Fig. 8, guides the end 55 and also centers it and the head 57.

85

In the form shown in Fig. 5, the trays or pans 10' are supported by brackets 64, 64', 64², 64³, independently of the heating grids and heads, though the single tubular discharge end 55 of each grid would tend to support the pan at one end by its passage through the opening 65 in the pan and its sealing engagement with the metal about this opening at 66. The bolts 60 pass through holes 67 in the pan at the header end.

90

When the bolts 60 at this end are tightened the flange of the head 57 is held tightly against the end of the tray or pan and the latter is pressed against the flange of the discharge header at 68 to seal the entire joint.

95

It will be seen that each of the trays or

100

105

110

115

120

125

130

pans in this form is separately supported and the grid may be withdrawn from it while the tray or pan is in place, by removing the bolts 60 at the manifold, removing the manifold, withdrawing the bolts 60 at the header end and pulling the grid to the left until the tubular end 55 of the head 57 is substantially free, then raising the grid sufficiently for the lower part of the head 56 to clear the end of the pan and continuing the withdrawal movement. The pan may then be removed.

The distributing passage 69, by which the steam is distributed in head 56 to the different grid pipes, is shown as largely within the downwardly extending portion of the head. The pipes 20 may be cast or otherwise secured in the head 56.

As will be evident, each pan can be removed longitudinally with its grid, if desired, when the manifold 18' has been moved out of the way and the bolts have been withdrawn from head 57.

The right hand ends of the pans in Fig. 5 are shown as having depressed bottoms 70 for the purpose of accommodating the flanges 59, without raising the grid pipes excessively in the pans. It is desirable to have the grid pipes barely covered with liquid and for some purposes it is also quite desirable to have the total depth of liquid low.

The pans are shown as provided with relatively low outer sides 71, end 61 and partial ends 72 of a height but slightly in excess of the height of liquid which is intended to be maintained. They have inner guards, shields or deflectors 73 about both sides and one end as at 74 high enough to retain the foam in the pans. The deflector for the left hand ends, in Figs. 5 and 8 is provided by a plate 75 which may be secured to the head 56 in any suitable manner. I have preferred to show it as detachably connected therewith and have secured it by bolts 76 passing through ears 77 integral with the grid head. When made detachable, it may be removed when the grid pipes are to be withdrawn from the pan, allowing it to come nearer the end of the pan than would otherwise be possible without interference with the end of the pan when the grid pipes are removed.

The deflectors 73 extend into engagement with the end 61, shutting off liquid flow laterally past the deflectors at this point. In view of this plate 75 need not engage with the bottom of the pan at any point. The spaces between the sides of the pan and the side deflectors, and also between the partial ends 72 and the right hand end deflector provide channels communicating with the body of the pan below the foam line through apertures 78. These channels 79 terminate in end walls 79' and permit discharge of liquid from the pans through discharge openings 80 and gutters 81 after the level has

risen over that of the weir 82. The discharge is directed into the body of the next pan by the gutter and is delivered, in this form, preferably at the same end of the pan as that at which the inlet liquid was received.

In operation, the fluid is admitted through the supply pipe 11' into the first pan and the liquid therefrom flows through it lengthwise out through the apertures 78, channels 79, outlet opening 80 and gutters 81 into the second pan, and thence progressively into the last pan, from which it may be withdrawn to storage or through any suitable waste-way connected with pipe 7' or the float chamber.

The blow-off 4 here affords drainage for condensate and for water used in flooding for general cleansing purposes. In the latter use the float is disconnected to allow a large quantity of water to pass through.

Where used as one of a series of cells, the steam enters through the pipe 17 from the next higher pressure and discharges through the vent and trap at the discharge end of the pans. The evaporation from the pans may be carried to a lower pressure cell by means of pipe 49.

The pans shown in Fig. 6 are substantially identical but differ slightly in width. On account of the narrowing space for the top of the upper pan, I have shown its bottom as flanged at 83 to give the additional width desirable for reliable support upon the brackets. The lowermost pan has no channels, discharge 80 nor gutters for drainage.

The form shown in Fig. 10 represents a modification of the structure shown in Fig. 1 in that the liquid residuum in the bottom of the tank does not extend across the width of the tank and loading of the blow-off is shown.

Here the cell 1 is supplied with a longitudinal partition 84 in the bottom upon one side of which, at 85, the residuum is stored. The tank is connected with a float chamber 6, both beneath and free from the water level by pipes 7 and 8' for the same purpose as in Fig. 1 of regulating fluid inlet to the upper pan by the height of the liquid level. A gage glass 86 is connected with the tank outside of the storage chamber at the bottom and at its top in order to indicate accumulation of liquid there and with the air space of the tank to indicate the water height.

Outlet of the stored liquid is provided through aperture 87 and the extent of opening of this aperture may be manually regulated by slide 88, adjusted by nut 89 upon bracket 90 outside the casing. This makes the rate of flow of liquid regulable with great exactness, whereas the regulation permissibly by valve 5 in the structure of Figs. 1 and 5 is obviously rather rough.

In order to retain additional control over

the blow-off and make its action automatic. I have shown globe-valve 92, whose closure is weighted by lever 93 pivoted in bracket 94. This is intended primarily for use where the cell is one of several used in multiple effect evaporation.

It will be evident that the various features of my invention shown in the different forms thereof, are illustrative merely of the many forms in which these features might be presented and that the individual parts of my invention have utility and advantage independently and in other combinations, as well as in combination with the others shown.

It will be evident that the character of the sectioned manifold, where sectioning is applied, pans, connections and adjustment used in Fig. 1, may be varied greatly, without departing from the spirit and scope of my invention; that the manifold sections need not be utilized as closures of the ends of the pans, this being a matter of additional convenience and economy aimed at in the best constructions of my invention; that the protections against foaming, particularly at the discharge point may be varied greatly in position and character; and that the various features by which the expense and time of manufacture and assemblage are saved may be greatly varied by engineers, in view of the instruction given by me herein. It will be evident that the connection, arrangement and construction of the manifolds, grid pipes, heads and pans, in the form shown in Fig. 5, may also be greatly varied by engineers, in view of the disclosure made by me herein and without departing from the spirit and scope of my invention; that separability of the grids and trays or pans may be secured by other constructions; that the path of flow of the discharge fluid in the pans may be changed; that different temperature accommodation may be used with partial benefit and that the storage may be separated from the lower pan without being against the casing of the cell.

Having thus described my invention, what I claim as new and desire to secure by Letters Patent is:—

1. In a device of the character stated, a casing, a sectional steam manifold, a discharge header, a plurality of trays and a steam grid for each tray, the grids being separably connected to the header and one connected to each section of the manifold.

2. In a device of the character stated, a sectional steam manifold and a discharge header in combination with steam grids and trays, one grid for each tray, each grid being connected with one of the sections of the manifold and separably connected with the header.

3. In a device of the character stated, a casing, a sectional steam manifold and a

discharge header in combination with steam grids and trays, one grid for each tray, each grid being connected with one of the sections of the manifold and separably connected with the header, and the trays being separably connected with the grids. 70

4. In a device of the character stated, a steam manifold, a discharge header, a plurality of grids connected between the manifold and the header and a tray adapted to be separably connected about each grid. 75

5. In a device of the character stated, a casing, a sectional inlet manifold, a plurality of grids, one connected with each section, a plurality of trays, one about the pipes of each grid, a discharge header separably connected with the grids, means for connecting the sections of the manifold and an adjustable support for the manifold sections. 80

6. In a device of the character stated, a casing, a plurality of units, each comprising a section of inlet manifold, a grid and a tray about the grid, a steam discharge connection for the grids, a steam inlet connection for the first manifold section and an adjustable support for the last unit. 85 90

7. In a device of the character stated, a casing, a steam inlet manifold therefor, a plurality of grids and trays thereabout connected with the manifold, a steam discharge connection for the grids passing through the casing and an expansion joint for the discharge connection expandible in the direction of the length of the grids. 95

8. In a device of the character stated, a steam inlet manifold having lateral extension, a plurality of pipes secured therein and an outlet head for said pipes forming a grid, a discharge header for said outlet and an open-ended tray removably secured about said pipes and closed at its ends by the lateral extension of the manifold and the outlet head. 100 105

9. In a device of the character stated, an open-ended tray and a steam grid fitting within the tray and closing its ends to form a pan. 110

10. In a device of the character stated, a steam grid, a tray fitting about the grid and transversely movable with respect thereto in combination with means directed transversely of the grid for removably securing the tray about the grid. 115

11. In a device of the character stated and as an article of manufacture, a section of steam manifold, a grid connected therewith, a discharge steam terminal at the opposite end from the manifold and a tray removably mounted about the grid. 120

12. In a device of the character stated and as an article of manufacture, a section of steam manifold, a grid connected therewith forming pan ends, a discharge steam terminal for said grid, an open-ended tray about

- 8
- said grid and means for forcing the tray into contact with the ends in a direction perpendicular to the length of the tray.
13. In a device of the character stated, a pan having an outlet whose upper edge is raised above the bottom of the pan to maintain fluid level therein, in combination with a foam deflector protecting the outlet from direct flow over its upper edge and apertured in its lower part to admit fluid to said outlet.
14. In a device of the character stated and as an article of manufacture, an open-ended tray, having sides and a discharge opening whose upper edges are raised above the bottom of the tray, but lie below the upper edges of the sides.
15. In a device of the character stated, and as an article of manufacture, an open-ended tray, having sides and a discharge opening whose upper edges are raised above the bottom of the tray, but lie below the upper edges of the sides in combination with a foam deflector protecting against direct flow from the body of the tray over the top of the discharge opening.
16. In a device of the character stated, inlet and outlet steam connections, a steam grid comprising pipes and ends, connected therewith and the said ends being adapted to form pan ends, in combination with an open-ended tray adapted to fit about the grid pipes and be closed by the grid ends to form a pan.
17. In a device of the character stated, a steam grid in combination with a tray inclosing a part of the grid removable therefrom and supported by the grid.
18. In a device of the character stated, a casing, a steam manifold, a discharge header, a plurality of grids connected with the manifold and separately connected with the header and a plurality of trays, one connected to each grid at the header end thereof.
19. In a device of the character stated, a steam manifold, a discharge header, a plurality of grids between the manifold and header removably connected with the header and a plurality of trays fitting about the grids and closed at the ends by the ends of the grids.
20. In a device of the character stated, a plurality of trays, heating grids and connections for the trays, a float chamber connected to maintain a predetermined liquid level, a float in said float chamber, an inlet for the first pan, a valve in said inlet and a connection between the float and valve to regulate the liquid inlet by the height of liquid in the float chamber.
21. In a device of the character stated, a tray, in combination with a steam grid adapted to enter the tray and coöperating with the tray to form a pan therewith.
22. In a device of the character stated, a plurality of pans, arranged one above another and having outlets from each pan to the next below near the ends of the pans and near opposite ends in the case of adjoining pans, in combination with foam deflectors, one for each outlet, protecting each outlet from direct flow over its upper edge and apertured at its lower part to admit fluid to said outlet.

JOSEPH KUEN.
